(57) **CLAIM**

The ornamental design for a shark fin swimming harness, as shown and described.

DESCRIPTION

FIG. 1 is a left side elevation view of the shark fin swimming harness of the present invention, a person to whom the shark fin swimming harness is attached being shown in broken lines for illustrative purposes only;

FIG. 2 is a right side elevation view thereof;

FIG. 3 is a front elevation view thereof;

FIG. 4 is a rear elevation view thereof;

FIG. 5 is a top plan view thereof; and,

FIG. 6 is a bottom plan view thereof.

The broken lines shown in FIG. 1 are for illustrative purposes only and do not form part of the claimed design.
